WINDOW OPERATING MECHANISM

Application filed September 16, 1929. Serial No. 392,995.

The invention relates to window operating mechanism and refers more particularly to an operating mechanism for a ventilator of an interiorly screened frame. One of the objects of the invention is to so construct the operating mechanism that the aperture in the screen for the operating mechanism is closed without the necessity of an extra shutter. Another object is to provide an improved operating mechanism with novel means for locking the operating rod in its various positions. With these as well as other objects in view, the invention resides in the novel features of construction and combinations and arrangements of parts as more fully hereinafter set forth.

In the drawings:—

Figure 1 is an interior elevation of a screened window having an operating mechanism embodying my invention;

Figures 2 and 3 are cross sections on the lines 2—2 and 3—3 respectively of Figure 1;

Figures 4 and 5 are cross sections on the lines 4—4 and 5—5 respectively of Figure 2;

Figure 6 is a view similar to Figure 1, showing a modification;

Figures 7 and 8 are cross sections on the lines 7—7 and 8—8 respectively of Figure 6;

Figure 9 is an enlarged sectional elevation 30 of a portion of the mechanism;

Figure 10 is an end elevation thereof.

As shown in Figures 1 to 5, inclusive, 1 is the frame, 2 is the vertically pivoted ventilator for the frame opening and 3 is the screen 35 for the frame opening. This screen is located at the inner side of the frame 1 and is secured thereagainst. The lower portion of the lower bar 4 of the screen has the notch or opening 5 for the passage of the mechanism 40 for operating the ventilator.

The operating mechanism comprises the support 6 extending longitudinally of the lower bar of the frame 1 and secured thereto by the screws 7. This support extends transversely of the frame and inwardly and is formed with the notch 8 to receive the lower bar 4 of the screen, the support registering with the portion of the lower bar having the notch or opening 5. 9 is the operating rod 50 having the handle 10 secured to one of its

ends and pivotally connected at the other of its ends to the bracket 11, which latter is secured to the lower bar of the ventilator by the screws 12. This operating rod is longitudinally slidably mounted in a transverse opening 13 in the cylindrical guide 14, which is housed within the support 6 and journaled therein at its upper and lower ends. This guide is located at one of the inner corners of the support, the upright wall of which is flanged inwardly at 15 and 16 to terminate adjacent diametrically opposite points of the guide, the portion of the upright wall between the flanges being apertured and the operating rod extending through this aperture.

The operating rod 9 is provided with the downwardly opening longitudinally spaced recesses 17 for alternatively receiving the upper end of the pin 18 in the guide 14, whereby the operating rod may be held in various positions of longitudinal adjustment. 19 is a bowed spring extending within the transverse opening 13 of the guide above the operating rod and bearing on the latter to force the same toward the pin. By lifting the operating rod it may be released from the pin, after which the operating rod may be adjusted to adjust the ventilator.

With this construction, the support for the operating mechanism forms a housing for a part of the operating mechanism. The housing and the guide for the operating rod close the screen opening through which the operating mechanism is adapted to extend. The guide is rotatable so that the operating rod has both a lever and a sliding action.

In the modification shown in Figures 6 to 10, inclusive, the window and screen construction is substantially the same as that of Figures 1 to 5, inclusive. The support 20 is generally similar to the support 6 and is secured to the frame in the same manner. The operating rod 21 has fixedly secured to one end the handle 22 and rotatably secured to the other end the coupling 23 which is pivotally connected to the bracket 24 upon the ventilator. 25 is the cylindrical guide corresponding to the guide 14 and journaled at its upper and lower ends in the support 20 near one of its inner corners. This guide

25 is provided with a transverse opening which has the end portion 26 threaded and the intermediate portion 27 tapered from the threaded end portion. 28 is a collar having 5 a polygonal (square, as shown) opening for sleeving over the operating rod 21. The end portion 29 of this collar is threaded to engage the threaded end portion 26 and the other end portion 30 is formed of tapered or 10 wedge-shaped segments separated by the sawcuts 31. The tapered end portion 30 is adapted to engage the tapered intermediate portion 27 upon turning the collar in one direction and to be clamped thereby upon the 15 operating rod. The turning of the collar may be accomplished by the turning of the operating rod about its longitudinal axis.

With the construction as above described, it will be seen that I have provided a simple 20 and effective construction of mechanism for operating the ventilator. Also that I have provided a simple means controlled by the operating rod for locking the operating rod in its various positions of longitudinal ad- 25 justment.

What I claim as my invention is:

1. The combination with a frame and a movable ventilator, of an operating mechanism for said ventilator, comprising an apertured support fixedly secured upon said frame, an operating rod extending through the aperture and a rotatable guide for said rod journalled upon said support and closing the aperture therein. 30

2. The combination with a frame and a movable ventilator, of an operating mechanism for said ventilator, comprising a fixed housing having an aperture, an operating rod extending through the aperture, and a 40 rotatable guide for said rod journalled in said housing and closing the aperture.

3. The combination with a frame, a movable ventilator and a screen against said frame apertured for the operating mechanism, of an operating mechanism for said ventilator comprising a fixed housing concealing the aperture in said screen and apertured for the operating rod, an operating rod extending through the aperture of said 50 housing, and a rotatable guide for said rod journalled in said housing and closing its aperture.

4. The combination with a frame and a movable ventilator, of an operating mechanism for said ventilator comprising a housing fixedly secured to said frame and having an aperture, an operating rod extending through the aperture, a rotatable guide for said rod journalled in said housing and closing the aperture, and means carried by said 55 guide and effective upon a predetermined rotation of the rod about its longitudinal axis to lock the rod against longitudinal movement.

5. The combination with a frame and a

movable ventilator, of an operating mechanism for said ventilator comprising a housing fixed to said frame and having an aperture, a rotatable guide journalled in said housing and closing the aperture therein, said 70 guide being formed with a bore through which said operating rod extends, said bore having tapered and threaded portions, and a contractible collar sleeved upon said rod and extending into said bore, said collar having tapered and threaded portions cooperating with the corresponding portions of the bore for effecting contraction of the collar upon a predetermined rotation of the rod whereby the latter is secured against longitudinal movement. 75

6. The combination with a frame and a movable ventilator, of an operating mechanism for said ventilator, comprising a support, an operating rod having one end connected to the ventilator for swinging and rotative movements relative thereto, and means carried by said support and cooperating with the rod upon rotation thereof to 80 lock the same from longitudinal movement. 85

7. The combination with a frame and a movable ventilator, of an operating mechanism for said ventilator comprising a support fixedly secured to said frame, an operating rod having one end connected to the 90 ventilator for swinging and rotative movements relative thereto, a rotatable guide for said rod journalled upon the support, and means associated with said guide and cooperating with the rod upon rotation of the latter 100 to lock the same against longitudinal movement.

8. The combination with a frame and a movable ventilator, of an operating mechanism for said ventilator, comprising a housing fixedly secured to said frame and having an aperture in one side wall thereof, an operating rod for said ventilator extending through the aperture, a rotatable guide for said rod journalled in said housing and closing the aperture, and means dependent upon relative rotation of said rod and guide for locking the rod from longitudinal movement. 105

9. The combination with a frame and a movable ventilator, of an operating mechanism for said ventilator, comprising a housing fixedly secured to said frame and having an aperture in one side wall thereof, an operating rod for said ventilator extending through the aperture, a rotatable guide for said rod journalled in said housing and closing the aperture, and means carried by said 110 guide for locking said rod against longitudinal movement.

10. The combination with a frame and a movable ventilator, of an operating mechanism for said ventilator, comprising a support fixedly secured to said frame, an operating rod connected to the ventilator for actu- 120

ating the same, a rotatable guide for said rod journaled upon the support, and means dependent upon relative rotation of said guide and rod for locking the latter from longitudinal movement.

5 In testimony whereof I affix my signature.

CLYDE W. KELLY.
